Patented Dec. 9, 1924.

UNITED STATES PATENT OFFICE.

THEODORE HUTNIKOW, OF BROOKLYN, NEW YORK.

DOUBLE VOICE FOR TOYS.

Application filed January 12, 1922. Serial No. 320,715.

To all whom it may concern:

Be it known that I, THEODORE HUTNIKOW, a citizen of Russia, residing at Brooklyn, county of Kings, and State of New York, have invented certain new and useful Improvements in Double Voice for Toys, of which the following is a specification.

This invention relates to improvements in sound devices, for toys, particularly for dolls.

In the known devices of this kind a "ma-ma" voice is produced by forcing compressed air through a reed, and by articulating the sounds produced by the lip of said reed by passing suitable valve discs successively through a rubber lip.

This arrangement works in one direction only, and the doll must be completely turned over after each sound production.

It is the principal object of the present invention to improve these known devices of this kind by providing novel means for producing a "ma-ma" voice and unarticulated sounds by one and the same operating means, so that it will not be necessary to turn a doll completely over in order to make her cry or produce other sounds.

In practice it has been discovered that the movable stem carrying the valve discs is apt to easily become disengaged from its guide disc provided with a hole for this purpose and that consequently the entire device became disarranged.

It is another object of the invention to avoid this disadvantage by substituting a sleeve attached to the weighted bellows ring which is longitudinally displaceable on a stationary stem attached to one of the discs forming the bellows chamber, so that the sleeve may freely move without the danger of becoming disengaged.

Other objects and advantages of my invention will become more fully apparent as the specification proceeds, and will then be specifically pointed out in the appended claims.

In the accompanying drawing forming a material part of this disclosure:

Figure 1 is a side view of a casing or body containing the device constructed according to the present invention, and adapted to be set into a doll body to form a chamber therein for the device.

Figure 2 is an end view of the casing, Figure 1.

Figure 3 is a longitudinal section through the same.

A cylindrical casing 10 for instance a piece of mailing tube stock has glued there-to or otherwise secured to its inner walls a pair of spaced discs 11 and 12.

To the lower disc 11 is firmly secured, in its center, a stem 13, on which a sleeve 14 is sliding, the lower end of which is secured to a weighted perforated disk 15. A small rubber bellows 16 or a bellows made of any other suitable material is attached at one end to the disk and with its other end to the disc 12.

The discs 11 and 12 are provided with small openings 17 and 18 communicating with the space under disk 15 and the interior of the bellows 16 respectively, and to the outer faces of the discs 11 and 12 are glued or secured in any other suitable manner over said openings 17 and 18 the sound boxes 19 and 20 respectively.

A reed 21 is set into an opening of the box 20 and is provided with a lip 22, while a reed 23 is set into an opening of the box 19 and provided with a lip 24.

A box 25 is secured to disc 12 and box 20 and carries a diaphragm 26 provided with a central opening 27 through which the valve discs 28 and 29 on sleeve 14 pass successively through the lip formed by the opening in the diaphragm for articulating the sound produced by the lip 22 of the reed 21.

From the foregoing it will be clear, that any movement of the doll will either produce the articulated "ma-ma" sound or unarticulated sounds, the "ma-ma" sounds being made by the air escaping through reed 21 upon the folding of the bellows under the sliding weighted disk 15 by the engagement of the discs 28 and 29 with the lip formed by the opening in the diaphragm during their successive passage, or unarticulated sounds caused by lip 24 when the air is forced through reed 23.

It will be clear that any disengagement of the valve operating sleeve 14 sliding along stem 13 will be positively avoided.

It is to be understood that the device shown is merely illustrated as an example

and that changes may be made in the specific arrangement of my device and in the construction of its minor details without deviating from the scope and spirit of my 5 invention.

Having thus described my invention, what I claim as new and desire to secure by Letters Patent of the United States is—

1. A double acting sound producer for 10 toys comprising a body, perforated discs secured between the inner walls of said body in spaced relation to each other to form a chamber, a stem secured to one of said discs, a sleeve sliding along said stem, a weighted 15 perforated disk to which said sleeve is secured with one of its ends, a bellows in said chamber, means for producing a sound by the air escaping through the perforation of said discs upon the operation of said 20 bellows in either direction, and means for articulating the sound produced at one end of said body for producing a "ma-ma" voice.
2. A double acting sound producer, for 25 toys comprising a hollow tubular body, a pair of perforated discs forming with the inner walls of said body a central chamber, a weighted sliding perforated disk in said 30 chamber, a bellows formed with said last named disk and one of said discs within said chamber, a stem secured with one of its ends to one of said discs, a sleeve longitudinally displaceable on said stem and secured with one of its ends to said weighted perforated disk, a reed chamber over the per-

foration in each of said discs, a reed in an 35 opening of each of said chambers, a lip on each reed, and a means for articulating the sound produced by one of said reed lips at one end of said body.

3. A double acting sound producer for 40 toys, particularly dolls, comprising a hollow tubular body, a pair of spaced discs provided with eccentrically arranged perforations forming a chamber within said body, a stem secured at one of its ends in 45 the middle of one of said discs and passing through the other, a sleeve longitudinally displaceable on said stem to slide thereon, a weighted perforated disk to which one 50 end of said sleeve is secured, a rubber bellows secured at one end to said perforated disk and at the other to one of said pair of spaced discs, a box on the outer face of each disc over the said perforations in the discs, each box having an opening, a 55 reed in the opening of each of said boxes, a lip on said reeds, a box on one of said discs and one of said reed boxes, a perforated diaphragm in said box, and a pair of 60 lip discs on said sleeve adapted to successively pass through the lip formed by the central perforation of said diaphragm for accentuating the sound produced by the lip on one of said reeds.

In testimony whereof I have affixed my 65 signature.

THEODORE HUTNIKOW.
